UNITED STATES PATENT OFFICE.

ARTHUR S. ALEXANDER, OF NEW YORK, N. Y., ASSIGNOR TO J. ALEXANDER MANUFACTURING COMPANY, A CORPORATION OF NEW YORK.

DESIGN FOR A BEZEL.

55,230.

Specification for Design.

Patented May 25, 1920.

Application filed September 19, 1919. Serial No. 325,023. Term of patent 14 years.

To all whom it may concern:

Be it known that I, ARTHUR S. ALEXANDER, a citizen of the United States, residing in the county of New York, city of New York, State of New York, have invented a new, original, and ornamental Design for a Bezel, of which the following is a specification, reference being had to the accompanying drawing, forming a part hereof.

In the drawings:

Figure 1 is a front view of my improved design.

Fig. 2, is a section on the line 2—2 of Fig. 1.

I claim:

The ornamental design for a bezel, substantially as shown.

This specification signed this 19th day of September, 1919.

ARTHUR S. ALEXANDER.
